US00D769884S

(12) **United States Design Patent** (10) **Patent No.:** **US D769,884 S**
Zhu (45) **Date of Patent:** **** Oct. 25, 2016**

(54) **DISPLAY SCREEN OR PORTION THEREOF WITH GRAPHICAL USER INTERFACE**

(71) Applicant: **Huawei Device Co., Ltd.**, Shenzhen (CN)

(72) Inventor: **Qiqi Zhu**, Shenzhen (CN)

(73) Assignee: **Huawei Device Co., Ltd.**, Shenzhen (CN)

(**) Term: **14 Years**

(21) Appl. No.: **29/468,452**

(22) Filed: **Sep. 30, 2013**

(51) LOC (10) Cl. **14-04**

(52) U.S. Cl.

USPC **D14/485**
